CLAIM

We claim the ornamental design of a lattice structure for footwear, as shown and described.

DESCRIPTION

This application is a continuation of, claims priority to and the benefit of U.S. patent application Ser. No. 16/899,586, filed Jun. 12, 2020 entitled “Rapid-Entry Footwear having a Compressible Lattice Structure,” and such application is incorporated herein by reference in its entirety for all purposes.

FIG. 1 is a side perspective view of a lattice structure for footwear;

FIG. 2 is a second side perspective view thereof;

FIG. 3 is a side view thereof;

FIG. 4 is a rear view thereof; and,

FIG. 5 is a second side view thereof.

The broken lines showing the remainder of the shoe are for environmental purposes only, and form no part of the claimed design.
